UNITED STATES PATENT OFFICE.

HUGH J. CLINE, OF WEST PALM BEACH, FLORIDA.

CYCLE-HAND-GRIP-ATTACHING MEANS.

1,290,716.

Specification of Letters Patent.

Patented Jan. 7, 1919.

Application filed April 6, 1918. Serial No. 227,145.

To all whom it may concern:

Be it known that I, HUGH J. CLINE, a citizen of the United States, and a resident of West Palm Beach, in the county of Palm Beach and State of Florida, have invented certain new and useful Improvements in Cycle-Hand-Grip-Attaching Means, of which the following is a specification.

This invention relates to cycle hand grips and more particularly to an improved structure for attaching the hand grips to the handle bars of a motorcycle, bicycle, or the like, and the primary object of the invention is to provide an attaching mechanism which will securely attach the hand grips to a handle bar, without necessitating the employment of glue or analogous adhesive and in such manner that loosening of the hand grips upon the handle bars, or the accidental disconnection between the two will be prevented.

More specifically, the object of this invention is to provide an attaching means as specified which comprises a handle bar gripping ring composed of a pair of substantially semi-circular sections having their outer and inner surfaces roughened, a wedge ring and a ferrule which engages the wedge ring and the hand grips for forcing the wedge grip over the gripping ring to cause the latter to securely grip the handle bar of the cycle and further to dent the ferrule, forcing the teeth formed thereby into the hand grips to prevent accidental movement of the ferrule with respect to the hand grips.

Other objects of the invention will appear in the following detailed description, taken in connection with the accompanying drawings forming a part of this specification, and in which drawing:

Figure 1 is a side elevation of a hand grip showing the same attached to a handle bar.

Fig. 2 is a section on the line 2—2 of Fig. 1.

Fig. 3 is an enlarged longitudinal section through the attaching means.

Fig. 4 is a view of the handle bar gripping ring showing one section thereof in side elevation and the other section in section.

Fig. 5 is a section through a modified form of the ferrule.

Referring more particularly to the drawings, 1 designates a hand grip of any ordinary type employed upon bicycles, motor-

cycles and the like, and 2 indicates a portion of a handle bar of the cycle. The hand grip 1 is provided with the usual type of longitudinally extending centrally disposed recess 3 in which the handle bar 2 extends. A handle bar gripping ring 5 is mounted about the handle bar 2 and engages the squared end 6 of the hand grip 1. The handle bar gripping ring 5 is composed of a pair of substantially semi-circular sections 7 and 8 which are wedge-shaped in cross section as clearly shown in Fig. 4 of the drawing and which have their inner surfaces roughened. The inner roughened surface of the ring 5 is provided for biting into and securely gripping the handle bar 2, while the outer surface is adapted to grip the inner surface of the wedging ring 9 which is mounted about the gripping ring 5 and forced there-over, by the forcing of the ferrule 10 outwardly toward the free end of the hand grip 1. The ferrule 10 has its innermost end 11 rolled, as clearly shown in Fig. 3 of the drawing to about one edge of the wedging ring 9, for forcing this ring over the gripping ring 5, which forcing action causes the roughened inner surface of the ring 5 to bite into the handle bar 2, to securely connect this ring to the handle bar and its outer roughened surface to bite into the wedging ring 9 for securely connecting the gripping ring and the wedging ring. After the ferrule 10 has been forced over the hand grip to the limit of its movement, it is dented as shown at 12, to provide inwardly projecting teeth 13 which bite into the hand grip 1 and prevent movement of the ferrule with respect to the hand grip 1, thus providing a secure and firm connection between the hand grip 1 and the handle bar 2, which will not work loose or permit movement of the hand grip independently of movement of the handle bar. The wedging action of the rings 5 and 9 will frictionally grip the inner surface of the ferrule at the outer surface of the ring 9 and hold these members in secure connection.

In Fig. 5 of the drawings, a modified form of the invention is shown. The modified form of the invention comprises a ferrule 10^a which has its edge 11^a bent inwardly, to form a wedge-shaped portion 12^a for engagement with the outer surface of the sections 7 and 8 of the bar gripping ring 5. When the ferrule 10^a is employed, the wedging ring 9 is eliminated, in that the wedging

portion 12^a serves the same function as the wedging ring 9.

The ferrules 10 and 10^a taper inwardly toward their central axes, as they extend to ward the rolled edges 11 and 11^a respectively.

Having thus fully described the invention, what is claimed is:

1. The combination with a cycle handle bar and a hand grip mounted thereon, of means for attaching said hand grip to said handle bar including a handle bar gripping ring having its bar engaging surface roughened, a ferrule mounted over said ring, and circular wedging means adapted for wedging engagement with the outer surface of the gripping ring.

2. The combination with a cycle handle bar and a hand grip mounted thereon, of means for attaching said hand grip to said handle bar including a handle bar gripping ring, a wedging ring mounted about said gripping ring, and a ferrule engaging said wedging ring and said hand grip, said gripping ring having its inner bar engaging surface roughened.

3. The combination with a cycle handle bar and a hand grip mounted thereon, of means for attaching said hand grip to said handle bar comprising a handle bar gripping ring, a wedging ring mounted about said gripping ring, and a ferrule engaging said wedging ring and said hand grip, said gripping ring composed of a pair of sections having their facing ends slightly spaced.

4. The combination with a cycle handle bar and a hand grip mounted thereon, of means for attaching said hand grip to said handle bar including, a handle bar gripping

ring wedge-shaped in cross section, a wedging ring mounted about said gripping ring, and a ferrule engaging said wedging ring and said hand grip, said ferrule being dented to provide teeth for embedding in said hand grip.

5. The combination with a cycle handle bar and a hand grip mounted thereon, of means for attaching said hand grip to said handle bar including, a handle bar gripping ring wedge-shaped in cross section, a wedging ring mounted about said gripping ring, and a ferrule engaging said wedging ring and said hand grip, said ferrule being dented to provide teeth for embedding in said hand grip, said gripping ring having its outer and inner surfaces roughened.

6. The combination with a cycle handle bar and a hand grip mounted thereon, of means for attaching said hand grip to the handle bar including, a handle bar gripping ring wedge-shaped in cross section, and having its inner surface roughened, a wedging ring mounted about said gripping ring, and a ferrule engaging said wedging ring and said hand grip.

7. The combination with a cycle handle bar and a hand grip mounted thereon, of means for attaching said hand grip to the handle bar including, a handle bar gripping ring wedge-shaped in cross section, and having its inner surface roughened, a wedging ring mounted about said gripping ring, a ferrule engaging said wedging ring and said hand grip, said ferrule being dented to provide teeth which are embedded in said hand grip to prevent movement of the ferrule independent of movement of the hand grip.

HUGH J. CLINE.
